UNITED STATES PATENT OFFICE.

IRWIN P. DILLON, OF LAWRENCE, MASSACHUSETTS, ASSIGNOR OF ONE-HALF TO HENRY C. KING, OF SAME PLACE.

DESIGN FOR A BEATER-TROUGH PLATE FOR PAPER MANUFACTURE.

SPECIFICATION forming part of Design No. 32,170, dated January 30, 1900.

Application filed December 21, 1899. Serial No. 741,194. Term of patent 14 years.

To all whom it may concern:

Be it known that I, IRWIN P. DILLON, a citizen of the United States, residing at Lawrence, in the county of Essex and State of Massachusetts, have invented and produced a certain new and original Design for a Beater-Trough Plate for Paper Manufacture, of which the following is a specification, reference being had to the accompanying drawings, forming 10 a part thereof.

In the drawings, Figure 1 represents my design in perspective. Fig. 2 is a perspective view thereof from a different point of view. Fig. 3 is a transverse vertical section on line 3, 15 Fig. 1.

The leading or material feature of my design for a beater-trough plate consists of a hollowed or sloping trough having a high and narrow portion at one end a , the trough growing deeper and wider throughout its length 20 toward the opposite end or side of the plate at a' , the rear wall or surface a^2 of the trough being curved downwardly and inwardly along the back part of the trough, while at the opposite or front side of the trough there is an 25 overhanging lip a^3 , projecting at a^4 from the

edge or wall a^5 of the trough and extending downwardly into the trough, the lower edge a^6 of said lip being curved obliquely forward and terminating in a substantially horizontal portion a^7 . The rear wall a^2 extends back from the left-hand end of the said top edge a^4 in an irregular curve and forwardly with a wide sweep, terminating at a^{10} , opposite the end of the wall a^5 , so that the trough extends 30 from its narrow end at the junction of the said rear wall and front wall with an expanding and approximately convolute sweep partially about said front wall, and the depending portion a^3 hangs over into said trough at about 35 opposite the middle thereof.

Having fully described my design, what I claim is—

The design for a beater-trough plate, substantially as herein shown and described. 45

In testimony whereof I have signed my name to this specification in the presence of two subscribing witnesses.

IRWIN P. DILLON.
